US0D1039512S

(12) **United States Design Patent** (10) Patent No.: **US D1,039,512 S**
(45) Date of Patent: ** Aug. 20, 2024

(54) **HEADSET**

(71) Applicant: **Microsoft Corporation**, Redmond, WA (US)

(72) Inventors: **Monique Chatterjee**, Seattle, WA (US); **Matthew C. Harvey**, Seattle, WA (US); **Sara Catherine Masaschi**, Boston, MA (US); **Richard T. Hanks**, Arlington, MA (US)

(73) Assignee: **Microsoft Corporation**, Redmond, WA (US)

(**) Term: **15 Years**

(21) Appl. No.: **29/853,541**

(22) Filed: **Sep. 16, 2022**

(51) LOC (14) Cl. **14-01**

(52) U.S. Cl.

USPC **D14/205**

(57) **CLAIM**

The ornamental design for a headset, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a headset showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in FIGS. 1-8 show portions of the headset that form no part of the claimed design.
